UNITED STATES PATENT OFFICE.

JAMES SUMNER BLANKENSHIP, OF BEND, OREGON.

HEADLIGHT MECHANISM.

Application filed November 3, 1925. Serial No. 66,580.

To all whom it may concern:

Be it known that I, JAMES SUMNER BLANKENSHIP, a citizen of the United States, residing at Bend, in the county of Deschutes and State of Oregon, have invented certain new and useful Improvements in Headlight Mechanisms, of which the following is a specification, reference being had to the accompanying drawings.

10 This invention relates to headlight mechanisms and has relation more particularly to a mechanism of this kind especially designed and adapted for use in connection with automobiles, and it is an object of the invention 15 to provide means whereby the lamps comprised in the mechanism may be turned aside at will to prevent the glare from interfering with the driver of an approaching car.

Another object of the invention is to provide a mechanism of this kind comprising lamps supported for turning movement about vertical axes having associated therewith means for normally maintaining the lamps straight ahead together with means 25 operable at will to swing said lamps to one side.

The invention consists in the details of construction and in the combination and arrangement of the several parts of my improved headlight mechanism whereby certain important advantages are attained and the device rendered simpler, less expensive and otherwise more convenient and advantageous for use, as will be hereinafter more 30 fully set forth.

The novel features of my invention will hereinafter be definitely claimed.

In order that my invention may be the better understood, I will now proceed to 40 describe the same with reference to the accompanying drawings, wherein:

Figure 1 is a view partly in section and partly in top plan illustrating a mechanism constructed in accordance with an embodiment of my invention in applied position;

Figure 2 is a view in bottom plan of the supporting means for the lamps and the structure directly associated therewith;

Figure 3 is a view partly in side elevation and partly in section illustrating the mounting of one of the lamps as herein disclosed;

Figure 4 is a sectional view taken substantially on the line 4—4 of Figure 2;

Figure 5 is a fragmentary sectional view taken substantially on the line 5—5 of Figure 1;

Figure 6 is a view in elevation with a portion broken away of the operating lever comprised in the mechanism;

Figure 7 is a view in perspective of a supporting post as herein employed.

Figure 8 is a longitudinal sectional view taken through the guide sleeve employed in connection with the radiator of the vehicle.

As disclosed in the accompanying drawings, radially disposed posts 1 are carried by the front fender structure of a motor driven vehicle, each of said posts at its upper end being provided with a laterally disposed plate 2. Secured, as at 3, to each of the plates 2 is an extension 4 carried by an end portion of an oval-like plate 5. The longitudinal axes of the plates 5 are in parallelism and forwardly extended with respect to the vehicle. The plates 5 are arranged at 75 the extremities of a cross member 6 and preferably integral therewith.

Each of the plates 5 has disposed from below through its central part a sleeve 7 provided at its lower end with an outstanding head 8 closely adjacent to the plate 5. Disposed through the sleeve 7 is a shank 9 depending from a headlight H, said headlight H being held to the sleeve 7 for rotation therewith through the medium of the clamping screw 10 threaded upon the lower end portion of the shank 9 and having close contact with the head 8 of the sleeve 7.

The head 8 is provided with an outstanding arm 11 having its outer or free end portion operatively engaged, as at 12, with an end portion of a rod 14, said rod 14 being operatively engaged, as at 15, with a plate 16. The connections 15 of both of the rods 14 are at opposite sides and in radial alignment with the mounting 17 for the plate 16. This mounting 17 comprises a pin supported by and bridging the space between the side arms 18 of a U-shaped member 19 bolted or otherwise secured, as at 20, to the cross member 6 and at a point preferably to one side of its longitudinal center. The plate 16 is provided with an arcuate groove 21 concentric to its mounting 17 and through which is disposed a bolt 22 or the like carried by the side arms 18 of the member 19 and also bridging the space between said side arms. Above and below the plate 16, the pin 17 is surrounded by the coil springs 23, an extremity of each of said springs being attached, as at 24, to the bolt 22 while the opposite end portion is suitably anchored,

as at 25, to the plate 16. These springs 23 provide means whereby the plate 16 is constantly urged in a direction to maintain the headlights H in their straight ahead position.

The straight ahead position of the headlights H is further maintained by a coil spring 26 encircling a stud 27 depending from each of the plates 5 and having one end portion 28 extended and secured to the outer portion of the adjacent arm 11 while the opposite end portion 29 of said spring is extended and secured to a lug 30 depending from the plate 5. The lug 30 also serves as a stop with which the outstanding finger 31 carried by the head 8 comes in contact when the headlights H are in their straight ahead position and thereby assuring such normal adjustment of the headlights.

It is to be noted that the arm 11 and finger 31 carried by one head 8 are reversely related to the similar elements of the second head with the associated parts in relative assembly. This is done so that both of the headlights H will have unitary swinging movement upon rocking or rotation of the plate 16 and in the same general direction.

The plate 16 is provided with an arcuate edge 32 the same being grooved as shown in Figure 5 to receive an end portion of a flexible member 33. This member 33 is suitably anchored or attached, as at 34, to an outstanding lug 35. This member 33 is directed through a sleeve 36 extended through the radiator R at a preferred point thereof. The member 33 is then extended rearwardly and operatively secured, as at 37, to a lever 38 suitably clamped to the steering column of the vehicle. The member 33, as herein disclosed, is directed through a suitably positioned opening 39 formed in the dash D and coacts with a guide pulley 40 secured to the dash in proper position with respect to the opening 39. The lever 38 is provided with a latch mechanism 41 coacting with a rack 42 carried by one of the supporting members 43 for the lever 38.

Normally, the headlights H are disposed straight ahead but in the event it is desired to turn the same to one side, as to the right, to prevent the glare from said lights interfering with the driver of an approaching car, it is only necessary that push be im-

posed upon the lever 38 and said lights will be swung to one side in accordance with the extent of movement of the lever 38. When the lever 38 is returned, the headlights H will automatically assume their straight ahead position.

From the foregoing description it is thought to be obvious that a headlight mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A headlight mechanism comprising, in combination, a plate, a supporting means therefor, a rotatable member carried by the plate, a headlight secured to said member, means for limiting the rotary movement of the member in one direction, means for normally maintaining said member at such limit of movement, a rotary plate, an operative connection between the rotary plate and the member for imparting rotary movement to said member in the opposite direction, and means operable at will for moving the rotary plate in one direction.

2. A headlight mechanism comprising, in combination, a plate, a supporting means therefor, a rotatable member carried by the plate, a headlight secured to said member, means for limiting the rotary movement of the member in one direction, means for normally maintaining said member at such limit of movement, a rotary plate, an operative connection between the rotary plate and the member for imparting rotary movement to said member in the opposite direction, means operable at will for moving the rotary plate in one direction, and means for automatically moving the rotary plate in the opposite direction.

In testimony whereof I hereunto affix my signature.

JAMES S. BLANKENSHIP.
